Attorney

UNITED STATES PATENT OFFICE.

VICTOR T. C. PETERSON, OF ATLANTA, NEBRASKA.

END-GATE CONSTRUCTION.

Application filed August 5, 1924., Serial No. 730,238.

To all whom it may concern:

Be it known that I, VICTOR T. C. PETERSON, a citizen of the United States, residing at Atlanta, in the county of Phelps and State 5 of Nebraska, have invented certain new and useful Improvements in an End-Gate Construction, of which the following is a specification.

This invention relates to improvements in 10 end gates for wagon bodies and has for its principal object to provide an end gate construction which is strong and durable, the same being provided with a swinging door for cooperation with an opening formed in 15 the end gate whereby grain or the like within the wagon box may be discharged therefrom. Fastening means are associated with the door for securing the same in engagement with the opening for preventing any 20 leakage of the grain through the opening.

A further object of the invention is to provide an end gate of the above mentioned character which will be simple in construction, inexpensive, and furthermore adapted 25 for the purposes for which the same is designated.

Other objects and advantages of this invention will become apparent during the course of the following description.

In the accompanying drawing forming a 30 part of this specification and in which like numerals designate like parts throughout the same:

Figure 1 is a side elevation of my improved end gate.

Figure 2 is a sectional view taken approximately on line 2—2 of Figure 1.

Figure 3 is a fragmentary sectional view taken approximately on line 3—3 of Figure 40 2, and

Figure 4 is a fragmentary sectional view taken approximately on line 4—4 of Figure 1.

In the drawing, wherein for the purpose 45 of illustration is shown the preferred embodiment of my invention, the numeral 1 designates generally my improved end gate, the same being preferably constructed of sheet metal. The end gate comprises the spaced outer and inner walls 2 and 3 respectively, the same being of such size as

to fit in the open end of the wagon body, not shown, in the manner well known in the art.

For the purpose of spacing the walls comprising the end gate, with respect to each other, the channelled shaped member 4 extends between the outer edges of the outer and inner walls respectively and any suitable fastening means such as is shown at 50 extends through the wall and the channel shaped spacing member for securing the latter in proper position between the walls.

The walls of the end gate are cut away to provide an enlarged rectangular shaped opening in the end gate for the purpose of permitting grain or the like to be discharged from the wagon box without necessitating the removal of the end gate from the wagon box. The inner edge of the outer wall which 70 extends around the opening which is designated by the numeral 6 is disposed inwardly from the inner edge 7 of the inner wall 3 which extends around the opening formed in the end gate. The purpose of this construction is to provide a flange 8 on the inner side of the end gate around the opening formed therein for the purposes hereinafter to be more fully described. A channel shaped member 9 similar to the channel 80 shaped member 4 extends between the outer and inner walls adjacent the inner edges thereof as is clearly illustrated in Figures 2 and 4 of the drawing, the fastening means for securing the channel shaped member 8 85 being illustrated at 10.

Secured on the outer wall 2 adjacent the inner side edges 6 thereof are the elongated angle irons 11. The securing means associated with the channel shaped member 8 90 and the outer and inner walls also provide a means for securing the angle irons 11 on the outer wall. The angle irons extend from the bottom edge of the end gate on the outer wall to a point adjacent the upper edge thereof in the manner clearly illustrated in Figure 1. The purpose of the provision of the angle iron will be presently described. Co-operating with the opening formed in the end gate by cutting away the outer and inner wall is the metallic door 12. The metallic door also comprises the outer and inner

walls 13 and 14 respectively. A channel shaped member 15 similar to the channel shaped members above described extends between the edges of the walls of the door 12 for holding the same in spaced relation with respect to each other. The fastening means for securing the channel shaped member 15 is illustrated at 16. The metallic door 12 is hingedly supported at its upper end by means of the horizontally extending rod 17 which extends through the looped brackets 18 secured to the outer wall 13 of the door 12 at the upper edge thereof and a similar bracket 19 secured to the outer wall 2 of the end gate 1 adjacent the upper edge of the opening. The ends of the rod 17 are adapted to extend through suitable openings provided in the upper portion of the angle irons 11. The inner wall 14 of the door 12 is adapted for engagement with the flange 8 formed on the inner wall 3 of the end gate adjacent the opening therein in the manner clearly illustrated in Figures 2 and 4 of the drawing, and when in this position, the opening is closed by the door and the grain in the wagon box is prevented from leaking therethrough. Angle irons 20 similar to the angle irons 11 are secured to the outer side edges of the outer wall 13 of the door 12, the securing means 16 provided for the channel shaped member 15 also supports the angle irons 20 on the outer wall of the door. The angle irons 11 and 20 respectively are provided with registering openings 21 and 22 respectively adjacent the bottom of the end gate and the purpose thereof will be hereinafter more fully described.

For the purpose of locking the door 12 in engagement with the opening provided in the end gate, a pair of cooperating rods 23 and 24 are provided. The inner ends thereof are connected to a suitable operating lever 25 which is pivotally supported adjacent its lower ends as illustrated at 26 on the intermediate portion of the outer wall 13 of the door 12. The rods 23 and 24 extend horizontally in opposite directions and the outer ends thereof extend longitudinally through suitable casings 27 and 28 carried by the outer wall 13 of the door 12 adjacent the angle iron 20. The outer ends of the rods further extend through the registering openings 21 and 22 provided in the angle irons 11 and 20 respectively in the manner clearly illustrated in Figure 4 of the drawing, thereby preventing the door from swinging outwardly out of engagement with the opening. A collar such as is shown at 29 is carried by each of the rods adjacent the outer end thereof and is disposed within each casing and further adapted for engagement with the respective angle irons 20. Coil springs 30 encircle each of the rods and are disposed within each of the casings

between the inner wall of the casing and the collar 29 for normally holding the rods in locked engagement with the angle irons.

A handle 31 is associated with the upper end of the lever 25 for enabling the same to be moved in either direction and a segmental rack 32 is secured on the outer wall of the door for cooperation with the lever 25 for holding the same in any desired position and whereby the rods 23 and 24 may be held out of engagement with the openings provided in the angle irons in order to permit the doors to be swung to an open position. A suitable handle 33 is secured to the outer wall of the door 12 adjacent the bottom thereof for enabling the same to be grasped and swung upwardly in order to disengage the door from the opening and enable the grain in the wagon box to be discharged therethrough.

The provision of a metallic end gate of the above mentioned character, will render the same strong and durable and at the same time will be inexpensive. The simplicity in which the same is constructed enables the door to be readily and easily opened or closed as may be desired and when in a closed position, there will be no possibility of the grain in the wagon box leaking therefrom.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. An end gate structure including a pair of spaced parallel plates having registering openings therein, one opening being smaller than the other, channel irons holding the plates in parallel spaced relation, two of said channel irons being disposed along the edges of the openings, and a door for said opening including a pair of spaced parallel walls, channel irons holding the walls in spaced parallel relationship, a pair of angle irons on the plate having the larger opening, one on each side of said larger opening, a rod attached to the upper edge of the door and extended through the angle irons so as to hingedly mount the door on the wall having the larger opening so that it may be swung into the openings for closing both openings, and slideable rods on the door projectable through the angle irons.

2. An end gate structure including a pair of spaced parallel plates having registering openings therein, one opening being smaller than the other, channel irons holding the plates in parallel spaced relation, two of said channel irons being disposed along the edges of the openings, and a door for said opening including a pair of spaced

parallel walls, channel irons holding the walls in spaced parallel relationship, a pair of angle irons on the plate having the larger opening, one on each side of said larger opening, a rod attached to the upper edge of the door and extended through the angle iron so as to hingedly mount the door on the wall having the larger opening so that it may be swung into the openings for clos-

ing both openings, slidable rods on the door 10 projectable through the angle irons, spring means associated with the latter mentioned bars to hold them normally projected through the angle bars.

In testimony whereof I affix my signature.

VICTOR T. C. PETERSON.
